UNITED STATES PATENT OFFICE.

JOSEPH O. POLLACK, OF CHICAGO, ILLINOIS.

RING CONTRACTOR.

Application filed June 2, 1921. Serial No. 474,501.

To all whom it may concern:

Be it known that I, JOSEPH O. POLLACK, a citizen of the United States, residing at Chicago, in the county of Cook and State of Illinois, have invented certain new and useful Improvements in Ring Contractors, of which the following is a description.

My invention relates to improvements in ring contractors, whereby the internal diameter of a ring may be decreased or reduced. The principal objects of my invention are to provide a device of the kind described, which may be operated quickly, and will be simple, convenient, compact, durable and satisfactory for use wherever found applicable.

Heretofore it has been customary when reducing rings to cut away or remove a portion of the ring, and to then solder or weld the resulting split ends together. This method is cumbersome and costly, and takes more or less time, and it changes a seamless ring into a seamed one after the reduction in size. With my improved device it is not necessary to split the ring or remove the material therefrom, and the work may be done in a few moments. By using my improved device, a ring can be contracted without splitting the ring, and without injuring or marring the inside engraving on the ring or the setting thereof.

Many other objects and advantages of the construction herein shown and described will be obvious to those skilled in the art from the disclosures herein given.

To this end my invention consists in the novel construction, arrangement and combination of parts herein shown and described, and more particularly pointed out in the claims.

In the drawings, wherein like reference characters indicate like or corresponding parts,

Figure 1 is an elevation of the device assembled;

Fig. 2 is a vertical section therethrough, showing the ring in place;

Fig. 3 is a section taken substantially on the line 3-3 of Fig. 1;

Fig. 4 is a section taken substantially on the line 4-4 of Fig. 1, showing the ring before pressure has been applied thereto to contract it; and

Fig. 5 is a view similar to that shown in Fig. 4, after pressure has been applied and the ring contracted.

Referring to the drawings, wherein I have illustrated the preferred embodiment of my invention, 1 and 2 represent mating elements or sections cooperating to form a cylindrical ring-receiving member adapted to receive a ring 5, the interior of said sections being bored as at 3 so as to taper internally from end to end, there being a series of parallel spaced annular grooves or channels 4 formed in said bored wall, said grooves progressively varying in diameter from one end of the member to the other end. These grooves are substantially annular in outline when the sections 1 and 2 are assembled as shown. While I have shown two sections 1 and 2, the number may be as desired. In order that the sections 1 and 2 shall not have any longitudinal or lateral displacement when assembled, and thus avoid the possibility of throwing the semi-annular grooves out of alignment, the same are preferably made to interengage. As shown, I have positioned pins 6 on the plane edges of one of the mating members, so as to project beyond the said edges, and in the plane edges of the other cooperating mating element I have formed apertures, recesses or openings 7 adapted to slidably receive said pins.

Clamping means 8, comprising a collar, band or the like, is adapted to loosely encircle or surround said assembled mating elements 1 and 2, as shown in the drawings. The collar is radially bored and threaded as at 9 to receive a threaded screw 10 therethrough, said screw being movable radially through said collar so as to engage and bear upon one of the sections of the mating members 1 and 2. When the screw is moved radially inward it forces the sections 1 and 2 toward one another, causing the ring 5 held therebetween to be contracted or reduced in diameter.

The operation of contracting or reducing a ring will be clearly apparent from the drawings, and no detailed description of the method used therefor is thought necessary. The parts 1 and 2 as they are brought together, compress the material of the ring, thereby reducing the diameter. Usually not much reduction in diameter is desired, but with my device considerable reduction is possible, and in a few moments time.

It is apparent that any number of segments 1 and 2 may be used to make up the cylindrical body, the annular recesses or

channels 4 being formed in each of the segments so that they will register to form annular grooves, as shown, when the elements are assembled, but I have found it preferable 5 to use but two segments, because the fewer parts there are, the more cheaply the device can be constructed. The parts 1 and 2 may be of any desired material of sufficient hardness so that there will be little 10 danger of their breaking, these parts being preferably highly polished where they engage the ring so that there will be no scratching of the ring held therein.

An elongated slot recess 11 is formed radially of the ring-receiving members 1 and 2, said slot communicating with the tapered bore 3 along one side thereof. The purpose of this slot is clearly shown in Fig. 7, and is to receive the setting of a ring, the ring being positioned in the annular grooves 4 so that its setting projects into the slot 11. The ring can be then contracted without engaging the setting, thus preventing any possible injury or damage thereto.

25 For plain rings, or that is, rings without setting, I prefer to use a receiving member without the opening or recess 11.

Having thus described my invention, it is obvious that various immaterial modifications may be made in the same without departing from the spirit of my invention; hence I do not wish to be understood as limiting myself to the exact form, construction, arrangement and combination of parts 35 herein shown and described, or uses mentioned.

What I claim as new and desire to secure by Letters Patent is:

1. A ring contractor of the kind described 40 comprising a contractile member having a tapered bore adapted to receive a ring, and means for contracting said member to reduce the diameter of said ring.

2. A ring contractor comprising a contractile member having a tapered bore there-

through with a ring-receiving annular groove internally thereof, and opening onto said bore, and means for contracting said member.

3. A ring contractor comprising in combination a split contractile member having a tapered bore therethrough with a series of spaced annular grooves opening onto said bore, said grooves adapted to receive a ring selectively therein and clamping means surrounding said member for contracting it to reduce the diameter of said ring.

4. A ring contractor comprising a contractile member having a bore therethrough, a recess laterally of and communicating with said bore, whereby a setting at a point on the periphery of said ring projects into said recess, and means for contracting said member to reduce the diameter of said ring without engaging said setting.

5. A ring contractor comprising a contractile member having a tapered bore therethrough, a radial slot longitudinally of said member and communicating with said bore, said member being adapted to receive a ring therein having a setting at a point on its periphery, the setting projecting into said slot, and means for contracting said member without engaging said setting.

6. A ring contractor comprising a contractile member having a ring-receiving annular groove internally thereof, a radial recess communicating with said groove, whereby a setting on the periphery on said ring in the groove may project into said recess, and means for contracting said member without engaging said setting.

In testimony whereof, I have hereunto signed my name in the presence of two subscribing witnesses.

JOSEPH O. POLLACK.
